Thomas Ball's design for bust of

Daniel Webster

Patented 19th April 1853

No. 548

Ms. 548

Thomas Ball, of Boston, Mass.
Letters Patent No. 548. Dated Apr. 19th 1853.

The schedule referred to in these Letters Patent and making part of the same
To all persons to whom these presents shall come:

Be it known that I, Thomas
Ball, of Boston, in the County of Suffolk, and State of Massachusetts, have produced a new and original design of a bust of Daniel Webster, and I hereby declare that the said new design is fully described and represented in the following specification and accompanying drawing, to which reference is hereafter made.

As 548

The accompanying drawing is a front or "three quarters" view of the bust.

The bust is of colossal size and is mounted on a base or pedestal a a. The drapery b b b b, is arranged so as to leave the breast partly exposed as shown in the drawing.

Having thus described my new design I shall state my claim as follows.

What I claim as my production and desire to have secured to me by Letters Patent, is the new design of a bust of Daniel Webster of colossal size, as represented in the drawing above referred to.
